(57) **CLAIM**

The ornamental design for a cooking pan with strainer, as shown and described.

DESCRIPTION

FIG. 1 is a perspective view of a cooking pan with strainer showing our new design.

FIG. 2 is a right side view thereof.

FIG. 3 is a left side view thereof.

FIG. 4 is an enlarged front view thereof.

FIG. 5 is an enlarged rear view thereof.

FIG. 6 is a top view thereof.

FIG. 7 is a bottom view thereof.

FIG. 8 is an exploded perspective view thereof, shown with the strainer unattached to the cooking pan for completeness of illustration.

FIG. 9 is an enlarged right view of the strainer portion, shown separately for ease of illustration; the left view being a mirror image thereof.

FIG. 10 is an enlarged front view of the strainer portion thereof.

FIG. 11 is an enlarged rear view of the strainer portion thereof;

FIG. 12 is an enlarged top view of the strainer portion thereof; and,

FIG. 13 is an enlarged bottom view of the strainer portion thereof.
